DOUBLE HINGED LATCHED CLOSURE

Donald J. Kettleborough, Mendota, Ill., assignor to the United States of America as represented by the Secretary of the Army

Application June 9, 1955, Serial No. 514,401

11 Claims. (Cl. 220—57)

My invention relates to closures for containers and more particularly to closures of the type known as cam closures wherein a closure cap or a plug is hinged to the container and is forced into a seated position closing a container opening by cam means operatively associated with the closure. Such devices are particularly desirable in hand manipulated dispensing cans because such closures can be quickly opened and closed without the use of tools.

To be economical, such closures are preferably formed from sheet metal and typical examples of such closures are found in the U. S. Patents to Grice No. 2,365,695, dated December 26, 1944; Johnson No. 2,329,716, dated September 21, 1943; or Gardes, No. 2,364,206, dated December 5, 1944. In these and like forms of closures, sheet metal cams engage sheet metal cam lugs. Both the cams and lugs are exposed in use and hence susceptible to damage by being accidentally bent. Even a slight bending in the wrong direction is sufficient to prevent proper seating of the closure whereby leakage will occur. This is particularly dangerous and objectionable when the containers are filled with volatile and/or flammable liquids such as motor fuels.

A further objection to such prior art devices is that the cam lever, being necessarily exposed, can sometimes be actuated accidentally particularly after the parts become worn. To overcome this evil, attempts have been made, as in the Grice patent supra, to secure the cam lever in the seated position by an exposed spring latch which itself is susceptible of accidental actuation as an incident to rough handling.

With the foregoing in view, it is an object of the invention to provide an improved cam-type closure of the class described.

A further object is to provide an improved closure of the class described wherein the cam means is formed, arranged and located to be protected against accidental distortion or damage.

A further object is to provide independently of or in combination with a cam closure of the class described, an improved latch for securing the closure closed and/or improved means for protecting such latch from accidental actuation or damage.

A further object is to provide a cam closure for a container opening wherein a closure is hinged to the container at one side of the opening and has a free end which extends beyond the other side of said opening, and cam actuating means hinged to said closure in the region of said free end of the same.

A further object is to provide in a closure such as that last described, an impervious hand grip portion on said cam actuating means which is substantially horizontally disposed in spaced relation to said container when in the closed position, and latch means for securing the closure in the closed position, said latch means being wholly covered and protected by said hand grip portion in all positions of the parts.

2

Other objects and advantages reside in the particular structure of the invention, in the structure and design of the several elements forming the same, combinations and sub-combinations of such elements, all of which will be readily apparent to those skilled in the art upon reference to the drawing in connection with the following specification wherein the invention is shown, described and claimed.

In the drawing:

10 Figure 1 is a longitudinal, vertical sectional view of the invention applied to a container, the parts being shown in the open position;

Figure 2 is a like view, the parts being shown in the fully closed position;

15 Figure 3 is a fragmentary vertical sectional view showing certain of the parts in a partially closed position;

Figure 4 is an exploded perspective view of the actuating and latch means of the invention;

20 Figure 5 is a like view of the closure portion of the invention; and

Figure 6 is a perspective view of a base plate for the closure apart from the rest of the structure.

Referring specifically to the drawing, wherein like reference characters designate like parts in all views, 10 designates any suitable container such as the well known military can illustrated and which has a top wall 11, a carrying handle 12 and an opening 13 in the top wall. The opening 13 is defined by an embossment 14 which mounts a reinforcing sput 15. A vent tube 16 is in communication with the opening 13 through the flange of the sput 15 and embossment 14. Preferably, the upper portion of the embossment 14 is outwardly flared to provide beveled closure seat 17. The embossment 14, outwardly of the upper edge of the seat 17, is downwardly directed to provide a radially outwardly facing annular shoulder 18.

As best seen in Figures 1, 2 and 6, a base plate 20 is formed with a central opening 21 which closely embraces the aforesaid outwardly directed annular shoulder 18 on the embossment 14. The undersurface of the base plate 20 is complementary to the outer surface of the top wall 11 and is fixedly secured thereto in any suitable and well known manner as by welding, riveting or the like, not shown.

40 The base plate 20 has a rear portion 22 which is upwardly and rearwardly inclined along the similarly sloped fore portions of the handle 12. The free rear edge of the portion 22 is formed with a plurality of spaced hinge ears 23. The base plate 20 has a front portion which is formed with a pair of holes 24 therethrough, there being a hole 24 on each side of the central opening 21. The foreparts of the holes 24 are covered by rearwardly opening, hollow cam lugs or latch keepers 25, the purpose of which will be apparent hereinafter.

50 The next element of the closure is a closure carrier 26 which is in the nature of a hinge leaf and which is generally complementary in shape to the base plate 20. Thus, the carrier 26, as best seen in Figure 5, includes an upwardly directed rear portion 27 having a rear edge formed with spaced hinge ears 28. Such ears are aligned with and straddle or interfit with the ears 23 of the base plate. Any suitable hinge pin 29 connects together the ears 23 and 28 in a well known manner so as to hingedly connect the closure carrier 26 to the base plate 20.

60 55 Any suitable closure such as a cap or plug for the opening 13 is carried by the closure carrier 26. In the embodiment illustrated, the central portion of the carrier 26 is formed with a hole 30 in which is mounted a closure plug generally indicated at 31. Plug 31 comprises a cylindrical upper part 32 which has a close fit in the hole 30 and projects thereabove. It also includes

an outwardly flared lower part 33 which not only limits upward movement of the part 32 in the hole 30 but also secures a gasket 34 to the plug so that the gasket 34 sealingly seats on the gasket seat 17 when the parts are in the closed position, Figure 2. A ring or cap 35 is fixedly secured in any suitable manner, not shown, to the projecting end of the upper part 32 after assembly of the plug 31 to the carrier 26 so as to prevent withdrawal of the plug from the hole 30.

The front end of the closure carrier 26 is formed with any suitable hinge means such as the spaced and aligned hinge ears 36 which mount any suitable connection such as the hinge pin 37 whereby an actuator for the plug carrier is hingedly connected to the latter.

The carrier actuator is generally indicated at 38 and as best seen in Figure 4 is of inverted channel configuration. It includes a pair of laterally spaced legs 39 which straddle the carrier 26 and which have forward portions formed with aligned holes 40 in which are seated the opposite ends of the hinge pin 37. Forwardly of the holes 40, the free front ends of the actuator legs 39 are formed to provide cams 41 which comprise latch dogs when seated in the hollow latch-keeper providing cam lugs 25 of the base plate 20, as best seen in Figures 2 and 3.

The rear portions 42 of the actuator legs 39 are widened in an upward direction and connected together by an impervious integral web 43 of substantial width. The front and rear edges of the web 43 may be downwardly extended as at 44 and 45, respectively, to provide eaves for a purpose to be apparent hereinafter. The rear leg portions 42 are formed with aligned sockets or holes 46 for a latch pin 47 of a latch 48 now to be described.

As best seen in Figure 4, the latch 48 comprises a pair of laterally spaced and aligned bell crank portions 49 each having an upper horizontal arm 50 and a downwardly directed vertical arm 51. The outer ends of the horizontal arms 50 are connected together by an integral web of angular cross section providing a vertical front wall flange 52 and a horizontal floor flange 53, the latter providing a finger piece for actuating the latch. The latch pin 37 extends through holes 55 located in the bell crank portions 49 in the region of the intersection of the arms 50 and 51 whereby to mount the latch on the actuator for pivotal movement relative thereto.

The lower end of each vertical crank arm 51 is formed with lower and upper beveled strike engaging surfaces 58 and 59, respectively. The strikes comprise the upper edges 56 of latch-keeper providing notches 57 formed in the opposite side edges of the upwardly directed rear portion 27 of the closure carrier 20. The upper edges 59 of the latch dogs 54 are each formed with a keeper-engaging notch 60 for securing the dogs in the latched positions. The latch 48 is preferably spring loaded toward the latched position by any suitable spring such as the U-shaped spring 61 best seen in Fig. 4. Spring 61 has a bight 62 which partially encircles the latch pin 47 and which merges with forwardly directed upper and lower spring arms 63 and 64, respectively, and which bear respectively against the web 43 of the actuator 38 and the floor flange 53 of the latch web. If desired and as shown, the arms 63 and 64 may have upwardly and downwardly directed free ends 65 and 66 which seat respectively in recesses 67 and 68 in the webs 43 and 53 aforesaid.

In operation and with the parts in the open position of Figure 1, it will be seen that the carrier 20 and actuator 38 are fully extended to the rear and lie atop the handle 12. They are readily retained in this position by one hand of the operator while the can contents are being poured out of the opening 13 or they simply rest on the handle 12 while the can is filled through the opening 13.

To close the opening 13, the closure carrier is swung to the Figure 3 position wherein the plug 31 has entered the opening 13 but is not quite seated. At the same time, the actuator 38 is swung on its pivot 37 in a counter-

clockwise direction relative to the carrier so as to overlie the same. The cams 41 are disposed so as to enter the cam lugs or latch keepers 25. The continued movement of the actuator 38 in the counterclockwise direction cams the carrier 20 and plug 31 downwardly until the gasket 34 of the latter is sealingly engaged with the seat 17.

At about this time the beveled strike engaging surfaces 58, 59 of the latch dogs 54 have successively engaged the strikes 56 so as to swing the latch in a counterclockwise direction until the strikes are cleared and the spring 61 forces the latch dogs 54 into the notches 57 so as to seat the strikes 56 in the notches 60, as best seen in Figure 2.

To release the closure, one or more fingers are inserted beneath the webs 43 and 53, and upward pressure on the latch web 53 releases the latch dogs 54 from the latch keeper-providing strikes 56. The actuator 38 may now be pivoted in a clockwise direction until its latch dog-providing cams have been withdrawn from their latch keeper-providing cam lugs 25. The carrier and plug may now be unseated by an upward and rearward pull on the actuator 38.

It is apparent from the foregoing that the closure of the invention may be opened and closed by hand without the exertion of any great strength and without the need for any tools. At the same time, it is clear that the domed cam lug-latch keepers 25 provide a sheet metal structure of much greater strength than the usual sheet metal cam lugs. Likewise, their location is such that they are unlikely to be damaged in normal use. Also, the cam-latch dogs 41 utilize edge surfaces for greater strength and are completely protected in use by being housed in the keepers 25. Thus, they are unlikely to be deformed or broken in normal use. Slight lateral deformation of these cams does not effect the operation as long as the deformation is insufficient to prevent entry into the lugs or keepers 25.

It should be noted also that the latch 48 is almost entirely enclosed by a housing formed by the actuator portions 42, 43, 44 and 45, which cooperate with the rear carrier portion 27 to provide top, rear and side walls. It is not only protected against the elements but has no protruding parts which may be accidentally struck in normal usage so as to disengage the latch. In this connection, the forward eave 44 of the web 43 may be downwardly extended below the point shown and even below the plane of the floor flange 53 of the latch web. It is only necessary that there be room to insert one or more gloved fingers below the same. It should be noted that the rear eave 45 overlaps the free upper edge of the carrier rear portion 27 to provide a protecting joint when the parts are in the closed position.

Thus, it follows from the foregoing that the closure of the invention fulfills all of the objects of the invention and yet provides a closure which is readily and cheaply constructed of sheet metal parts or the equivalent.

Moreover, while I have shown and described what is now thought to be a preferred embodiment of the invention, it should be understood that the same is susceptible of other forms and expressions. Consequently, it is to be understood that I do not limit myself to the particular structures shown and described hereinabove except as hereinafter claimed.

I claim:

1. In a closure for a container having a wall formed with an opening therethrough; the improvement comprising a closure carrier and a closure carried thereby, hinge means mounting said carrier for movement to and from opened and closed positions, an actuator for said carrier, a second hinge in spaced parallel relation to said first-named hinge means and hingedly connecting said actuator to said carrier, at least one forwardly directed cam on said actuator, at least one hollow and rearwardly opening cam lug on said wall forwardly of said first-named hinge means, said actuator being swingable with and relative to said carrier in one direction to a partially closed position wherein said cam is received in said hollow cam lug,

said lug providing a fulcrum for said actuator for camming said carrier to said closed position upon continued movement of said actuator in the same direction relative to said carrier there being a latch for readily releasably securing rear portions of said actuator and carrier together when the latter is in said closed position, and said actuator including an inverted channel-shaped portion providing a housing overlying said latch and substantially entirely enclosing the same on at least three sides in both said opened and closed positions of said carrier.

2. In a closure for a container having a wall formed with an opening therethrough and a closure seat associated with said opening; the improvement comprising a base plate fixed to said wall and surrounding said opening, a closure for said opening, a plate-like closure carrier mounting said closure centrally thereof, a first hinge hinge means hingedly connecting said carrier and base plate together rearwardly of said opening, a pair of rearwardly opening cam lugs comprising integral upward extensions of said base plate, said cam lugs being disposed in laterally spaced and aligned relation on opposite sides of said opening forwardly thereof, an actuator for said carrier, said actuator being an inverted U-shaped member of substantially rigid sheet material and having a web and a pair of legs depending from opposite sides of said web in straddling relation to said carrier, said legs having forward extensions terminating in free front ends formed to provide laterally spaced and aligned latch dog-providing cams which project forwardly of said carrier, a second hinge means rearwardly of said cams hingedly connecting said actuator and carrier together for movement to and from open and closed positions, said cams being engageable with said cam lugs to provide fulcrums for camming said closure and carrier to a seated position upon movement of said actuator in one direction.

3. A closure according to claim 2, wherein said carrier includes an upwardly inclined rear portion having side edges formed with aligned notches providing a second pair of latch keepers, said notches being closed by said legs of said actuator when the latter is in said closed position, a spring latch pivotally mounted on said actuator beneath said web thereof, said latch including a pair of laterally spaced and aligned latch dogs located to engage said second pair of latch keepers upon movement of said actuator to said closed position, and said latch being enclosed on all but the front side by said legs and web of said actuator and said rear portion of said carrier, when said actuator is in said closed position.

4. A closure according to claim 3, wherein said web of said actuator includes a rearwardly depending eave overlapping said rear portion of said carrier when said actuator is in said closed position.

5. A closure according to claim 4, wherein said web includes a forwardly depending eave to provide forward protection for said latch.

6. A closure according to claim 5, wherein said latch includes a finger piece disposed entirely beneath said web in downwardly spaced relation thereto, and said finger piece being movable upwardly toward said web to disengage said second pair of latch dogs from their keepers.

7. In a closure for a container having a wall formed with an opening therethrough; the improvement comprising a closure carrier and a closure carried thereby, hinge means mounting said carrier for movement to and from opened and closed positions, an actuator for said carrier, a second hinge in spaced parallel relation to said first-named hinge means and hingedly connecting said actuator to said carrier, at least one forward directed cam on said actuator, at least one hollow and rearwardly opening cam lug on said wall forwardly of said first-named hinge means, said actuator being swingable with and relative to said carrier in one direction to a partially closed position wherein said cam is received in said hollow cam lug, said lug providing a fulcrum for said actuator for camming said carrier to said closed position upon continued

movement of said actuator in the same direction relative to said carrier, there being a latch for readily releasably securing rear portions of said actuator and carrier together when the latter is in said closed position, means mounting

5 said latch on said actuator, said carrier being formed to provide a latch keeper engaging said latch when said carrier is in said closed position to releasably secure said actuator against movement relative to said carrier, said actuator including an inverted U-shaped portion providing the roof and sides of a housing for said latch, and said carrier including two wall portions which are angularly directed relative to each other, and said wall portions cooperating with said U-shaped portion to provide a floor and a rear wall for said housing when said

15 actuator is in the closed position.

8. In a container closure, the combination with a container wall; of a base plate fixed to said wall, said base plate and wall being formed with aligned holes providing a plug seat, a plug carrier and a plug carried thereby, a

20 first hinge means at one side of said seat laterally thereof and hingedly connecting said base plate and plug carrier together for swinging movement of the latter into and out of a position seating said plug in said seat, said base plate being formed with at least one latch keeper laterally

25 of said seat and opposite said first hinge means, an actuator for said plug carrier, a second hinge means hingedly connecting said actuator and carrier together laterally of said plug, said actuator having a cam formed thereon in the region of said second hinge means, said

30 cam comprising a latch dog engaging said latch keeper in one position of said carrier to cam said carrier and plug into said seated position, a spring latch on said actuator opposite said second hinge means for readily releasably securing said actuator in a position holding

35 said plug in said seated position, said spring latch having a laterally spaced pair of spring latch dogs, said carrier being formed with a laterally spaced pair of latch keepers for said spring latch dogs, cooperating means on said actuator and carrier providing a housing for said spring

40 latch, and said housing having a top, rear and side walls.

9. In a container closure, the combination with a container wall; of a base plate fixed to said wall, said base plate and wall being formed with aligned holes providing a plug seat, a plug carrier and a plug carried thereby, a

45 first hinge means hingedly connecting said base plate and plug carrier together for swinging movement of said carrier into and out of a position seating said plug in said seat, said base plate being formed with a pair of laterally spaced latch keepers, each latch keeper being a rearwardly opening hollow domed portion of said base plate,

50 an actuator for said plug carrier, a second hinge means hingedly connecting said actuator and carrier together, said actuator having a pair of laterally spaced cams comprising latch dogs, said latch dogs being located in the region of said second hinge means, said latch dogs engaging and cooperating with said latch keepers in one position of said carrier to cam said carrier and plug into a seated position, a latch, means mounting said latch on said actuator in remote relation to said latch dogs, a

55 keeper for said latch, said keeper being disposed on said carrier in the region of said first-named hinge means, said actuator including a cover for said latch, and said cover including top and side walls together with forwardly and rearwardly depending eaves protecting said latch.

60 65 70 75 10. In a cam type closure for a container, the combination with a container opening, a hinged closure for said opening; of an actuator for said closure, means hinging said actuator to said closure for swinging movement to and from seated and unseated positions, cooperating cam means on said container and actuator for camming said closure to a closed position upon movement of said actuator to said seated position, latch means on said actuator and carrier for releasably securing said actuator and carrier together in said seated position, said actuator having

75

an inverted channel-shaped portion, said carrier having an upstanding wall portion, and said channel-shaped portion and wall portion cooperating in said seated position to provide a housing substantially entirely enclosing said latch means.

11. In a container closure, the combination with a container wall having an opening therein formed to provide a closure seat; of a closure carrier and a closure carried thereby, a first hinge means laterally outwardly of said seat hingedly connecting said carrier to said container for swinging movement of said closure into and out of a position seating said closure on said seat; an actuator for said closure carrier, a second hinge means hingedly connecting said actuator and carrier together laterally outwardly of said closure, cooperative cam-type latch dog and latch dog keeper means on said actuator and container for camming said closure into said seated position, said carrier having an end portion extending away from

said container wall, said end portion being formed with at least one opening therethrough, said opening providing spring latch keeper means, a spring latch carried by said actuator, said actuator including an inverted channel shaped portion enclosing said latch, said spring latch engaging said spring latch keeper means with said closure in said seated position to prevent disengagement of said latch dog and latch dog keeper means, and said end portion closing one end of said channel-shaped portion when the parts are in said seated position.
